RIVET SETTING TOOL

Rudolph M. Babel, Pawtucket, R.I., assignor to United Shoe Machinery Corporation, Boston, Mass., a corporation of New Jersey

Filed Aug. 14, 1962, Ser. No. 71,276

Term of patent 14 years

(Cl. D54—10)

Fig. 1

Fig. 2

Fig. 3

FIG. 1 is a right side elevation of a rivet setting tool embodying my new design;

FIG. 2 is a left side perspective view of the tool, as seen looking upwardly from the rear thereof; and

FIG. 3 is a right side perspective view, as seen looking downwardly from the front thereof.

The dominant features of my design reside in the portions shown in full lines.

I claim:

The ornamental design for a rivet setting tool, substantially as shown and described.
